(57) CLAIM

The ornamental design for a scissors, as shown and described.

DESCRIPTION

FIG. 1 is a top perspective view of a scissors according to a first embodiment of our new design;

FIG. 2 is a front elevation view of the scissors of FIG. 1;

FIG. 3 is a rear side elevation view of the scissors of FIG. 1;

FIG. 4 is a right side elevation view of the scissors of FIG. 1;

FIG. 5 is a left side elevation view of the scissors of FIG. 1;

FIG. 6 is a top plan view of the scissors of FIG. 1;

FIG. 7 is a bottom plan view of the scissors of FIG. 1;

FIG. 8 is a top perspective view of a scissors according to a second embodiment of my new design

FIG. 9 is a front elevation view of the scissors of FIG. 8;

FIG. 10 is a rear elevation view of the scissors of FIG. 8;

FIG. 11 is a right side elevation view of the scissors of FIG. 8;

FIG. 12 is a left side elevation view of the scissors of FIG. 8;

FIG. 13 is a top plan view of the scissors of FIG. 8; and,

FIG. 14 is a bottom plan view of the scissors of FIG. 8. The broken lines in the drawings illustrate portions of the scissors that form no part of the claim. The stippling represents a contrast in appearance.
